WATER DISCRIMINATION FUZE

Henry D. Saunderson, Riverside, Calif., assignor to the United States of America as represented by the Secretary of the Navy

Application March 15, 1956, Serial No. 571,851

3 Claims. (Cl. 102—76)

(Granted under Title 35, U.S. Code (1952), sec. 266)

The invention described herein may be manufactured and used by or for the Government of the United States of America for governmental purposes without the payment of any royalties thereon or therefor.

This invention relates to a fuze and more particularly to a water discrimination fuze which prepares a detonator within the fuze of a missile in response to the deceleration of the missile as it changes from a relatively high velocity in air to a much lower velocity in water.

Prior to this invention direct mechanical means have been utilized either manually or automatically actuated prior to or at the moment of release of a missile or alternatively by means of a timing device or a water flow meter after release. These devices were complex and subject to human failure and moreover were subject to mechanical failure.

Various missiles have a normal course that consists of an air flight followed by entry into water and a subsequent run under the surface of the water. It is desirable to prepare the detonator within the fuze of such a missile so as to arm the missile after it has entered the water. It is also desirable that such a missile not be armed by the normal and accidental shock forces that are encountered during handling and shipping, and that the fuze be simple, compact, and completely enclosed or sealed within the missile.

The water discrimination fuze of the present invention prepares the detonator within the fuze of a missile in response to the deceleration of the missile as it changes from a relatively high velocity in air to a much lower velocity in water.

One preferred embodiment of the present invention utilizes the inertia of a number of spring restrained masses that move sequentially as the missile is decelerated to unlatch a detonator carrying rotor which, after completion of its movement, causes mechanical alignment of the detonator with a charge within the missile and also closes electric contacts to arm the missile.

One object of the present invention is to provide a missile fuzing system which will not be actuated until after water entry.

Another object of the present invention is to provide a water discrimination fuze which will not be armed by the normal or accidental shock forces that are encountered during handling and shipping.

A still further object of the present invention is to provide a fuze which will only arm subsequent to the typical deceleration encountered by an air flight missile when it enters the water prior to a run under the surface of the water.

A still further object of the present invention is to provide a water discrimination fuze which is simple, compact, and completely enclosed or sealed within the missile.

Other objects and many of the attendant advantages of this invention will be readily appreciated as the same becomes better understood by reference to the following detailed description when considered in connection with the accompanying drawings wherein:

2

Fig. 1 is a pictorial view of one preferred embodiment of the present invention taken nearly normal to the direction of flight of the water discrimination fuze within a missile and with the arrow indicating the direction of flight of the missile;

Fig. 2 is a plan view of the fuze illustrated in Fig. 1 taken in the direction of flight if it were mounted within a missile;

Fig. 3 is an enlarged fragmentary cross-sectional view taken on line 3—3 of Fig. 2 showing two alternate leaves with their restoring springs and illustrating by phantom lines the unlatching of the second leaf by movement of the first leaf in response to inertial forces;

Fig. 4 is an enlarged view showing a pair of alternate leaves having a somewhat different shape but functioning in the same manner as the leaves of Fig. 3;

Fig. 5 is a graph showing the entry or initial deceleration with regard to the velocity of the missile such as a torpedo as it leaves the air and enters the water; and

Fig. 6 is a graph showing the relationship between time and deceleration of a missile such as a torpedo which has a specific entry velocity after it enters the water.

Referring now to Fig. 5, the entry deceleration of a specific missile, such as a torpedo, is given in terms of the entry velocity as the missile leaves the air and enters the water. After submergence, water drag continues to decelerate the missile, as shown in Fig. 6 for a specific missile having an entry velocity of 500 ft./sec., until it has a velocity determined by its prime mover. It will be seen from these curves that the overall deceleration of a missile, such as a torpedo, may vary from more than 100 to more than 5 times the acceleration due to gravity, as the velocity of the missile changes from a constant air flight velocity to a constant underwater velocity. Missile deceleration within the order of these magnitudes that extend over a predetermined time interval are required to prepare the water discrimination fuze of this invention to arm a missile and, therefore, shocks normally encountered during handling and shipping or accidental shocks do not prepare the detonator within the fuze.

One preferred embodiment of the fuze of the present invention shown in Figs. 1 through 3 in which the supporting frame 10 has secured thereto plates 11 and 12 machined at one end to form bearings with caps 13 and 14 and bridged by an electric contact-carrying member 15 rigidly fastened to the plates 11 and 12. A rotor 17 is rotatably mounted on a shaft 16 and has a hole 18 located at right angles to the axis of rotation in which a detonator is placed. Electric connections from such a detonator are made to terminate at a ground connection on the rotor and at a contact terminal 19 insulated from the rotor. One end of coil spring 20 is fixed to plate 12 and the other end of coil spring 20 is fixed to the extension of shaft 16. Detent pin 21 is mounted in the side of rotor 17.

Also secured to supporting frame 10 is a U-shaped bracket 22 through the side members of which rigidly secured shafts or pivots 23 and 24 carry a group of leaves 25, rotatable on pivot 23, and a group of leaves 26, rotatable on pivot 24. Each leaf 26 is rotatably mounted by a bearing 27 on pivot 24, as shown in Fig. 3, and has a pivot clearance slot 28, and, except for outermost leaf 25, a detent pin 29. Similarly, as shown in Fig. 3, each leaf 25 is rotatably mounted by a bearing on pivot 23 and has a pivot clearance slot (not shown) and a detent pin 31. Restraining springs 32 are secured to the base of bracket 22 and act on the edge surfaces of alternately mounted leaves 25 and 26 tending to restore them to a normal position, where pivot clearance slots such as 28 in contact with pivots 23 and 24 serve as

stops, as shown in Fig. 3 in phantom lines. Detent pins 29 and 31 rest on flat portions of the edges of leaves 25 and 26, each preventing rotation of its leaf until the next outermost leaf has previously been rotated. Bracket 22 and innermost leaf 25 are mounted so that detent pin 21 in the side of rotor 17 rests on the upper edge of innermost leaf 25 when in a normal position to latch rotor 17.

Operation

In the operation of the fuze the detonator-carrying rotor 17 is first latched by rotating leaves 25 and 26 in sequence from the outermost to the innermost leaf against the force of springs 32 and then rotating rotor 17 against coil spring 20 until detent pin 21 clears and then rests on the edge of innermost leaf 25. The leaves 25 and 26 are then released in sequence from the innermost to the outermost leaf to their normal positions. With rotor 17 in latched position, as shown in Fig. 1, the detonator (not shown) adapted to be placed in hole 18 is not in mechanical alignment with the charge within the missile and accidental detonation cannot fire the charge. Electric contact terminal 19 is also displaced from the electric contact 33 on member 15 so that automatic or mechanical closure of a firing switch, connected in a series circuit with a source of electric power, the contacts 19 and 33, and leads terminating in the detonator, cannot ignite the detonator while rotor 17 is latched.

When a missile with rotor 17 of its fuze latched leaves its air flight and enters water, a large entry deceleration of the missile takes place, as shown in Figs. 5 and 6. Since leaves 25 and 26 consist of spring-restrained and inertia-responsive masses all of the leaves will tend to move, but only outermost leaf 25 is free to rotate about its bearing 27 to a position where detent pin 31 is free to move which will unlatch adjacent leaf 26. Adjacent leaf 26 is now free to rotate, as illustrated by phantom lines in Fig. 3, provided deceleration of the missile continues and the inertial forces acting on the mass of leaf 26 exceed the restoring force of its restraining spring 32. It will be noted that for leaves 25 and 26 of equal masses and similar restraining springs 32, decrease in decelerations of the missile require correspondingly longer intervals for each leaf to move a given distance to unlatch the adjacent leaf. However this might result in too rapid response to high inertial forces at entry or no response to the smaller forces as the missile approaches its normal water velocity. Therefore it is usually necessary to vary the mass of leaves 25 and 26 and/or the restoring force of springs 32 to provide a step function which will approach the curve of Fig. 6. If deceleration of the supporting frame 10 continues due to water drag, successive leaves 25, 26 rotate in sequence, depending on the magnitude of their masses and on the restoring forces of springs 32, until detent pin 21 is free to move and unlatches rotor 17, which after rotation, mechanically aligns the detonator in hole 18 with the charge in the missile to align the explosive train and arm the fuze mechanically and also closes electric contact 33 on member 15 with contact terminal 19 on rotor 17 to arm the fuze in the missile electrically.

If the magnitude of deceleration of supporting frame 10 is sufficient in magnitude but not of proper duration to cause sequential rotation of all leaves 25 and 26, rotor 17 will not unlatch, leaves 25 and 26 which have unlatched will return to normal, and the missile will not be armed.

Alternate forms of leaves 34 and 35 are shown in Fig. 4 to illustrate the infinite variety of shapes and arrangements which will function in the device of the present invention. The leaves 34 and 35 are rotatable on pivots 36 and 37 and have detent pins 38 and 39 respectively. A somewhat longer slot 40 is shown to limit the movement of the leaves.

A subsequent improvement of the water discrimination fuze of the present invention is disclosed in the patent

applications of H. D. Saunderson for Water Discriminating Fuze, Serial No. 405,264, filed January 20, 1954.

Obviously many modifications and variations of the present invention are possible in the light of the above teachings. It is therefore to be understood that within the scope of the appended claims the invention may be practiced otherwise than as specifically described.

What is claimed is:

1. A water discrimination fuze comprising a rotor adapted for limited rotational movement about an axis, said rotor having an aperture adapted to receive a detonator and an electrical contact terminal, a plurality of leaves eccentrically mounted for movement by the deceleration forces resulting from entry of a missile into water, a pair of pivot pins for mounting said leaves, each of said leaves having a slot therethrough, alternate leaves being mounted on one of said pivot pins and the intermediate leaves being mounted on the other pivot pin with said pivot pins extending through the slot in the leaves which are not mounted thereon, spring restraining means adapted to engage said leaves and resist movement due to deceleration, the first of said leaves being free to move against said spring means when the missile is decelerated by water entry, the other of said leaves having latching means adapted to engage the next preceding leaf until said leaf has moved against the action of said spring means whereby said leaves are successively free to move under the forces of sustained deceleration, and means on said rotor engaging the last of said leaves and adapted to be disengaged when said leaf has moved under the forces of deceleration, and means adapted to move said rotor when released to a position where said fuze is armed mechanically and electrically.

2. A water discrimination fuze comprising a rotor adapted for limited rotational movement about an axis, said rotor having an aperture adapted to receive a detonator and an electrical contact terminal, a plurality of leaves eccentrically mounted for movement by the deceleration forces resulting from entry of a missile into water, a pair of pivot pins for mounting said leaves, each of said leaves having a slot therethrough, alternate leaves being mounted on one of said pivot pins and the intermediate leaves being mounted on the other pivot pin with said pivot pins extending through the slot in the leaves which are not mounted thereon, spring restraining means adapted to engage said leaves and resist movement due to deceleration, the first of said leaves being free to move against said spring means when the missile is decelerated by water entry, the other of said leaves having detent pins adapted to engage the next preceding leaf until said leaf has moved against the action of said spring means whereby said leaves are successively free to move under the forces of sustained deceleration, and a detent pin on said rotor engaging the last of said leaves and adapted to be disengaged when said leaf has moved under the forces of deceleration, and spring means adapted to move said rotor when released to a position where said fuze is armed mechanically and electrically.

3. In a shell fuze, a fuze body having a recess therein to receive a rotor, a rotor mounted in said recess and movable from a position in which said rotor is in fuze disarming condition to a position in which said fuze is armed, means for exerting a steady force for rotating said rotor from disarmed to armed position, a first latching plate pivotally mounted in position for latching said rotor against movement from disarmed to armed position, said latching plate having an outer end engaged with a stud secured to said rotor in position to prevent pivotal movement of said latching plate in response to exertion of said steady force, and said latching plate having a preponderance of mass located to exert a pivotal force to cause release of said outer end from said stud, upon development of a predetermined inertial force thereupon, and a second latching plate overlying the said first latching plate, said first latching plate having a stud projecting from a

face thereof into latching engagement with a surface of said second latching plate, said second latching plate being also pivotally mounted and being yieldingly biased into latching position and having its mass distributed to cause pivotal movement to releasing position, upon development of a predetermined inertial force thereupon.
